EXPLOSION MOTOR

Hector Eugène Mondragon, Neuilly-sur-Seine,
FranceApplication December 15, 1932, Serial No. 647,457
In France December 18, 1931

21 Claims. (Cl. 123—71)

This invention relates to explosion motors of the two stroke type, that is to say to explosion motors wherein the power piston receives a motive impulse during each revolution of the shaft.

5 One object of the invention consists in the provision of a simple and improved arrangement for carrying out the two stroke cycle above mentioned. A further object of the invention resides in a novel manner of providing ignition of the

10 explosive charge.

These and other objects of the invention will be apparent from the following description read in conjunction with the accompanying drawings which show one embodiment of the invention 15 merely by way of example and in which:

Fig. 1 is an axial section of the power mechanism taken at right angles to the crank shaft.

Fig. 2 is a longitudinal section thereof through the axes of the crank shaft and cylinder.

20 Fig. 3 is a section on line III—III of Fig. 2.

Fig. 4 is an enlarged cross section through line IV—IV of Fig. 1.

Referring to the drawings, reference numeral 1 denotes the power cylinder (or expansion cylinder) here shown with an integral head 2. At the upper end of said cylinder and adjacent this head one or more ports 3 are arranged through which burning gases pass during the expansion period and burnt gases during the exhaust period.

30 Suction and exhaust manifolds designated by 4 and 5 respectively are provided in a member 17 which houses the mechanism. Member 17 is carried by crank shaft case 19 and in turn supports casing 18 of power cylinder 1.

35 A power piston 6 is driven from motor shaft 9 to which it is connected by means of a pin 7, connecting rod 7 (represented by its axis) and crank pin 8.

40 Adjacent the inlet manifold 4 is formed an annular space 10 adapted, during the suction period as hereinafter described, to communicate with said manifold and is bounded on its lower side by the upper face of an annular compressor piston 11 driven from the shaft 9 through pin 14, connecting rod 13 and crank pin 12. The piston 11 slides on a sleeve which forms part of an auxiliary compressor piston 16 acting as and hereinafter termed a distributor. The space 10 is bounded on its upper side by the base 15 of the distributor 16 which is adapted to slide on the power cylinder 1. Space 10 is bounded on its outer side by the inside walls of member 17 in which both the distributor 16 and compressor piston 11 slide.

45 Distributor 16 is provided with one or more

chambers 20, symmetrically disposed around the general axis. Each chamber is formed on its outer face with an inlet port 21 for explosive mixture coming from the annular space 10 during the compression period and on its inner face with 5 port 22 adapted to serve as an outlet towards the power cylinder ports 3 during the explosion and expansion period.

In order to lead the explosive mixture from the space 10 to chamber 20 of distributor 16 one or 10 more outside channels or grooves 25 are provided which open into corresponding ports 23 and 24 arranged in member 17. This distributor 16 is driven through pin 28, connecting rod 27 and crank pin 26 of crank shaft 9 and these driving 15 members may all be duplicated as shown.

15 Recesses or grooves 29, Figs. 2 and 3, are provided in the walls of the power cylinder 1, to allow for the movements of connecting rod 27.

To start the mechanism, one or more spark 20 plugs located in the cylinder head at 30 or in the member 17 at 31, are used to produce explosion. In this latter case the plug is located so that the outside distributor ports 21 reach the corresponding port of the spark plug 31 at the 25 same time as the inside distributor ports 22 reach the power cylinder ports 3.

During the compression stroke, the explosive mixture incoming from chamber 10 may be cooled when going through channels 25 by means 30 of air cooled fins 34 located on the member 33 which forms the outer boundary of said channels. Said fins may even be water cooled, as shown in Fig. 4, at 32 and other fins may be added as shown at 35 and 36, the fins 35 being formed 35 integrally with the walls of member 17 (Fig. 4).

Distributor 16 may be made of two parts 16^a and 16^b fitted together and held by bolts or screws 37. The sleeve formed by the part 16^a slides 40 around the outer walls of power cylinder 1. Between ports 22 this sleeve is provided with one or more ports 38 which together with channels 39 mounted on the upper part of 16^b, and with exhaust manifolds 5, form one or more outlets for burnt gases from the power cylinder when said 45 ports 38 are in communication with the cylinder ports 3, during the exhaust period.

Crank pins 12 driving compressor piston 11 and crank pins 26 driving distributor 16 are so set with regard to power piston crank pin 8 that the 50 former leads said crank pin 8 by a small angle α while pin 26 lags behind said pin 8 by an angle β , the total angle $\alpha + \beta$ being as near a right angle as possible (see Fig. 1 where rotation is clockwise). 55 Piston rings are used wherever necessary to ob-

tain gastightness between the respective parts. They are shown in Fig. 1 at 40 on power piston 6 at 44 and 45, on compressor piston 11 at 41, 42, 43, on power cylinder 1 and at 46, 47, 48 on distributor 16.

The operation of the mechanism above described is as follows:

Owing to the small value of lead angle α the two pistons 11 and 6 travel almost together in either direction upwards or downwards.

In Fig. 1 the mechanism axis is supposed to be vertical and the distributor at its bottom dead centre. Compressor piston 11 and power piston 6 are shown going upwards, during the compression and the exhaust periods respectively.

On the compressor side, the explosive mixture sucked in to the chamber 19 during part of the preceding revolution is gradually forced into chambers 20 through ports 23 channels 25, ports 24 and 21, as the distance between the top of piston 11 and the base 15 of the distributor is constantly decreasing.

On the power cylinder side, piston 6 is expelling burnt gases of cylinder 1 to the atmosphere through ports 3 and 38, channels 39 and manifolds 5.

Distributor 16 commences its upward movement while pistons 6 and 11 still move upwardly.

On the compressor side the travel of piston 11 relatively to distributor 16 decreases and reaches its minimum when the respective velocities are equal and the top of piston 11 nearly touches the bottom part 15 of the distributor which marks the end of the compression period.

At this moment the lower edge of port 21 just reaches the upper edge of port 24, piston ring 48 prevents any further communication between chambers 20 and the compressor side while piston ring 42 prevents communication of chamber 20 with the power cylinder.

On the power cylinder side the exhaust period still goes on. On the compression side the distributor 16 still continues its upward movement and the travel of piston 11 relatively to distributor 16 begins to increase steadily from the above mentioned minimum value. When the lower edge 15 of the distributor piston reaches the lower edge of manifold 4, the suction period begins, the gas being drawn directly from the carburetor for instance, while there is as yet no communication between chambers 20 and power cylinder 1.

On the power cylinder side the exhaust stroke is nearing its end. Distributor 16 continues its upward travel until the lower edges of ports 38 reach the upper edges of ports 3, thus terminating the exhaust period. Power piston 6, still rising, will then compress burnt gases against cylinder head 2 of cylinder 1, thus increasing their temperature. During this period, the upper edges of port 22 in sleeve 16a have reached the lower edges of port 3 thus causing communication between chambers 20 and the interior of cylinder 1, also ports 21 have been brought opposite to the spark plug port 31. The compressed explosive gases in chambers 20 are then ignited either by spark plug 31 when the power mechanism is cold, or by contact through ports 3 with superheated compressed burnt gases. This latter alternative called ignition through secondary compression, may be facilitated by the insertion in the member 30 in the cylinder head of one or more well insulated metal points which remain red hot during operation. Angle α may be chosen to be suitable for either manner of producing the explosion.

Piston 6 reaches then its top dead centre and begins its downward movement in the expansion period of the cycle.

On the compressor side during the same upward movement of distributor 16 the suction period has been continuing. Then the distributor comes to its top dead centre and starts on its downward movement, the expansion period still continuing.

On the compressor side the relative travel between piston 11 and distributor 16 now reaches a maximum value. When the lower edge 15 of the distributor piston reaches the lower edge of manifold 4, the suction period is ended which takes place shortly after the maximum value. This period of time is calculated so that chamber 10 will be filled with an explosive mixture at atmospheric pressure, for full speed of the power mechanism, the relative travel being taken as about equal to that of the compressor piston 11 20 alone.

During the same downward travel of distributor 16 the lower edge of port 38 reaches the upper edge of port 3 and opens the exhaust, thus ending the expansion period at the time when piston 6 approaches its bottom dead centre, the upper edge of port 22 having previously passed the lower edges of port 3 thus cutting off the communication between chambers 20 and power cylinder 1. These chambers are again isolated from both the compressor and power cylinder until the lower edges of distributor port 21 reaches the upper edge of port 24 in member 17. At this moment the suction period has just ended and explosive mixture is once more forced into chambers 20 from chamber 19 through ports 21 and 24 and channels 25.

During this downward movement of distributor 16 power piston 6 has reached its bottom dead centre and has started on its up travel, the exhaust period thus continuing.

Then the distributor reaches its bottom dead centre the differential compressor and power pistons doing independently their work of compressing and exhausting respectively and the whole cycle begins again.

What I claim is:—

1. An explosion motor of the two stroke type described including in combination a power cylinder, a power piston movable within said cylinder, an annular auxiliary piston sliding on the outer surface of said cylinder and provided with a chamber in its walls, said chamber having an outlet port on its inner wall and an inlet port on its outer wall, a compressor piston sliding around said cylinder and arranged so as to form an annular space between said compressor piston and said auxiliary piston, a crank shaft, means to connect each of said pistons to said crank shaft, said means being relatively so disposed as to produce relative movement between said three pistons during each revolution, a housing surrounding said auxiliary and compressor pistons formed with a channel and inwardly directed spaced outlets for said channel, said channel and said outlets forming connecting means for said space and the inlet port of said chamber at one period of the travel of said auxiliary piston, means to allow introduction of an explosive mixture into said space at one period of each revolution and means to connect said chamber with the interior of said cylinder at a further period of each revolution.

2. An explosion motor of the two stroke type described, including in combination a power cylinder having a single gas opening, a power pis-

ton movable within said cylinder, an annular auxiliary piston sliding on the outer surface of said cylinder and provided with a chamber in its walls, a compressor piston sliding around said cylinder and arranged so as to form an annular space between said compressor piston and said auxiliary piston, a crank shaft, means to connect each of said pistons to said crank shaft, said means being relatively so disposed so as to produce relative movement between said three pistons during each revolution, said chamber having an outlet port adapted to coincide with said gas opening at one period of the movement of said auxiliary piston and having an inlet port, a housing surrounding said auxiliary and compressor pistons formed with a channel and inwardly directed spaced outlets forming connecting means between said space and the inlet port of said chamber at another period of travel of said auxiliary piston and means to introduce an explosive charge into said space at a further point of the travel of said auxiliary piston.

3. An explosion motor of the two stroke type described, including in combination a power cylinder having a single gas opening, a power piston movable within said cylinder, an annular auxiliary piston sliding on the outer surface of said cylinder and provided with a chamber in its walls and with an aperture coinciding with said gas opening adjacent the lower limit of movement of said auxiliary piston, a compressor piston sliding around said cylinder and arranged so as to form an annular space between said compressor piston and said auxiliary piston, a crank shaft, means to connect each of said pistons to said crank shaft, said means being relatively so disposed so as to produce relative movement between said three pistons during each revolution, said chamber having an outlet port adapted to coincide with said gas opening at one period of the movement of said auxiliary piston and having an inlet port, a housing surrounding said auxiliary and compressor pistons formed with a channel and inwardly directed spaced outlets forming connecting means between said space and the inlet port of said chamber at another period of travel of said auxiliary piston, and means to introduce an explosive charge into said space at a further point of the travel of said auxiliary piston.

4. An explosion motor of the two stroke type described, including in combination a power cylinder having a single gas opening, a power piston movable within said cylinder, an annular auxiliary piston sliding on the outer surface of said cylinder and provided with a chamber in its walls and with an aperture coinciding with said gas opening adjacent the lower limit of movement of said auxiliary piston, a compressor piston sliding around said cylinder and arranged so as to form an annular space between said compressor piston and said auxiliary piston, a crank shaft, means to connect each of said pistons to said crank shaft, said means being relatively so disposed so as to produce relative movement between said three pistons during each revolution, said chamber having an outlet port adapted to coincide with said gas opening at one period of the movement of said auxiliary piston and having an inlet port, a housing surrounding said auxiliary and compressor pistons formed with a channel and inwardly directed spaced outlets forming connecting means between said space and the inlet port of said chamber at another period of travel of said auxiliary piston, said housing hav-

ing an exhaust manifold, a guide member for the exhaust gases between the aperture of said auxiliary piston and said manifold and means to introduce an explosive charge into said space at a further point of the travel of said auxiliary piston.

5. An explosion motor of the two stroke type described including in combination a power cylinder, a power piston movable within said cylinder, an annular auxiliary piston sliding on the outer surface of said cylinder and provided with a plurality of chambers symmetrically peripherally spaced within its walls, a compressor piston sliding around said cylinder and arranged so as to form an annular space between said compressor piston and said auxiliary piston, a crank shaft, means to connect each of said pistons to said crank shaft, said means being relatively so disposed so as to produce relative movement between said three pistons during each revolution, said chamber having an outlet port adapted to coincide with said gas opening at one period of the movement of said auxiliary piston and having an inlet port, a housing surrounding said auxiliary and compressor pistons formed with a channel and inwardly directed spaced outlets forming connecting means between said space and the inlet port of said chamber at another period of travel of said auxiliary piston and means to introduce an explosive charge into said space at a further point of travel of said auxiliary piston.

6. An explosion motor of the two stroke type described, including in combination a power cylinder, a power piston moving within said cylinder, an annular auxiliary piston sliding on the outer surface of said cylinder provided with a chamber in its walls and having portions of different diameters, a compressor piston sliding on said portion of smaller diameter so as to form an annular space between said compressor piston and said auxiliary piston, a crank shaft, means to connect each of said pistons to said crank shaft said means being relatively so disposed as to produce relative movement between said three pistons during each revolution, means to allow introduction of an explosive mixture into said space at one period of each revolution, means connecting said space with said chamber at another period of each revolution and means to connect said chamber with the interior of said cylinder at a further period of each revolution.

7. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive cham-

ber with the power cylinder at another period of each revolution and means for allowing the exhaust of the burned and expanded gases from the power cylinder at a further period of each revolution.

8. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, an inlet port in the outer wall of the said chamber for the admission of the compressed explosive mixture, an outlet port in the inner wall of the same chamber for the admission of the power mixture into the power cylinder, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution and means for allowing the exhaust of the burned and expanded gases from the power cylinder at a further period of each revolution.

9. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, an inlet port in the outer wall of the said chamber for the admission of the compressed explosive mixture, means for igniting the explosive mixture in the explosive chamber, an outlet port in the inner wall of the same chamber for the admission of the compressed and ignited mixture into the power cylinder, a crank shaft, means for connecting each of the three above pistons to said crank shaft, said means being relatively so disposed so as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution and means for allowing the exhaust of the burned and expanded gases from the power cylinder at a further period of each revolution.

10. A two stroke explosion engine including in combination a power cylinder provided with an opening for the admission and the exhaust of the gases into and out of the said cylinder, a power piston, a compressor for the explosive mix-

11. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, the said auxiliary compressor piston being sliding on the power cylinder and provided with a cylindrical extension on which the main compressor piston is gliding, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution and means for allowing the exhaust of the burned and expanded gases from the power cylinder at a further period of each revolution.

12. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, a crank shaft, means for connecting each of the three above pistons to said crank shaft, said means including a crank pin driving the main compressor piston, a crank pin driving the auxiliary compressor piston, these crank pins being so set with regard to the power piston crank pin that the

- former of the said crank pins leads the power piston crank pin by a small angle while the second of the said crank pins lags behind said former by an angle of about 90°, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution and means for allowing the exhaust of the burned and expanded gases from the power cylinder at a further period of each revolution.
13. A two-stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution, means for igniting the explosive mixture during the connection of the explosive chamber of the auxiliary compressor piston with the power cylinder and means for allowing the exhaust of the burned and expanded gases from the power cylinder at a further period of each revolution.
14. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution, means for igniting by contact the compressed explosive mixture enclosed in the explosive chamber of the auxiliary compressor piston when the said explosive chamber is connected with the power cylinder.
15. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution, means arranged in the power cylinder for igniting the explosive mixture during the connection of the explosive chamber with the said power cylinder and means for allowing the exhaust of the burned and expanded gases from the power cylinder at a further period of each revolution.
16. A two stroke explosion engine including in combination a power cylinder, a power piston, a compressor for the explosive mixture, the said compressor including two annular pistons distinct from the power piston and arranged in a housing surrounding coaxially the said power cylinder, one of the said compressor pistons being a main compressor piston and the other being an auxiliary compressor piston provided with an explosive chamber in its walls, a crank shaft, means for connecting each of the three above pistons to said crank shaft, said means being relatively so disposed as to produce relative movements between said three pistons during each revolution of the crank shaft, means for allowing introduction of an explosive mixture into the space included between both annular pistons of the compressor at one period of each revolution of the crankshaft, means for admitting the compressed explosive mixture into the explosive chamber of the auxiliary compressor piston at another period of each revolution of the crank shaft, means for connecting said explosive chamber with the power cylinder at another period of each revolution, means for allowing the exhaust of the burned and expanded gases from the power cylinder at a further period of each revolution, means for compressing at the end of the exhaust period one part of the said burned and expanded gases at a pressure and temperature sufficiently high for igniting by contact the compressed explosive mixture enclosed in the explosive chamber of the auxiliary compressor piston when the said explosive chamber is connected with the power cylinder.
17. A two stroke explosion engine including in combination a power cylinder, a power piston, a compressor for the explosive mixture, the said

the said chamber of the compressed explosive mixture, a channel arranged in the housing of the compressor pistons with its both ends opened in the inner wall of the said housing and forming a connection between the compression chamber of the compressor and the inlet port of the above explosive chamber at another period of each revolution of the crank shaft of the engine, the said crank shaft, means for connecting each 10 of the three above pistons to said crank shaft, said means including a crank pin driving the main compressor piston, a crank pin driving the auxiliary compressor piston, these crank pins being so set with regard to the power piston crank pin that the former of the said crank pins leads the power piston crank pin by a small angle while the second of the said crank pins lags be-

hind said former by an angle of about 90°, an outlet port in the inner wall of the explosive chamber for connecting the said chamber with the opening of the power cylinder at a third period of each revolution of the above crank 5 shaft, means for igniting at that time the compressed explosive mixture enclosed in the explosive chamber of the auxiliary compressor piston, means for registering the opening of the power cylinder with the exhaust port of one of 10 the extension walls of the auxiliary compressor piston at a fourth period of each revolution of the engine, and a corresponding port arranged in the outer housing of the compressor pistons for the escape of the said gases. 15
